TOILET OR THE LIKE CABINET

James H. Dyett, Buffalo, N. Y., assignor to Hard
Manufacturing Company, Buffalo, N. Y.

Application June 5, 1944, Serial No. 538,867

1 Claim. (Cl. 312—189)

1

This invention relates to improvements in toilet cabinets or the like, such for example as are used in hospitals and institutions for holding and housing toilet articles or appliances for the convenience of nurses or the use of patients or inmates.

One type of cabinet rather extensively employed for such purposes comprises an upright body or casing provided at its upper or top portion with a sliding drawer adapted to contain small articles; beneath this a compartment for housing a wash basin or the like, which may be supported on a swinging bracket by which the basin can be shifted from a position within the compartment to a position convenient for use in front or outside of the compartment; and another or bottom compartment adapted to house or conceal a bedpan, or other receptacle or device, the cabinet being provided with a front door for opening and closing the compartments or portion of the cabinet chamber below the sliding drawer. In some cabinets of this type the front or outer door is also supplemented by an inner door or closure member for the bottom, or bedpan, compartment, so arranged that this compartment may be kept closed to conceal or isolate its contents when the outer door is opened to give access to the other compartment or compartments of the cabinet. Heretofore, in order to meet the demands of different users or purchasers of said cabinets, the manufacturer or dealer had to produce or stock cabinets of two different models, one equipped with the inner door and a cheaper one which did not have the inner door.

One object of my invention is to provide a cabinet of the type indicated which is equipped with the usual outer door, and with guide or mounting means for an attachable and removable inner door, whereby it is only necessary for the manufacturer or dealer to produce or stock a cabinet of a single model, which can be, according to the requirements of the purchaser or user, either furnished with or left without the inner door, without involving expense or labor, other than the cost of the inner door, when it is used.

Another object of the invention is to provide a practical, desirable and pleasing cabinet of the type indicated, which is of improved, novel construction.

Further objects and advantages of the invention will appear from the following specification of the preferred embodiment of the invention shown in the accompanying drawing, and the

2

novel features of the invention as set forth in the appended claim.

In said drawing:

Fig. 1 is a front view of a cabinet embodying my invention, showing the outer door open and the inner door in place, closing a bottom compartment of the cabinet, and showing the top drawer partly in transverse section.

Fig. 2 is a similar view thereof but showing the inner door raised to give access to the bottom compartment.

Fig. 3 is a fragmentary, sectional plan view thereof on a larger scale, on line 3—3, Fig. 1.

Fig. 4 is a side elevation thereof, partly in vertical section, showing the manner of placing the inner door in position and removing it.

Fig. 5 is a fragmentary, longitudinal sectional elevation of the cabinet showing the inner door raised against the top drawer.

As illustrated in the drawing, the casing or body 10 of the cabinet is of chambered or hollow, substantially rectangular form both horizontally and vertically, and is provided at its top or upper portion with a sliding drawer 11, which may be mounted in any suitable manner, as on supporting guides 12 at its opposite sides on the side walls of the cabinet to adapt the drawer to be slid into and out of the cabinet in the usual manner. The cabinet has a front or outer door 13, which may be hinged or mounted in any suitable manner for movement to open and close the front of the cabinet chamber below the drawer 11. Preferably, the chamber of the cabinet is divided by a horizontal partition or shelf 14, into two compartments 15 and 16, the upper of which is adapted to house a wash basin or other desired article or articles, and the lower of which compartments is ordinarily intended for housing a bedpan or other receptacle or appliance which it may be desired to keep concealed or enclosed when the front door 13 is opened.

As best shown in Fig. 3, the front edge of the partition 14 is spaced somewhat rearwardly away from the front door 13, when the latter is closed, so as to provide between the front door and the front edge of the partition 14, a vertical space within which an inner door or closure member 17 for the bottom compartment 16 is located and movable. Preferably, this inner door 17 is a sliding door or plate arranged to slide vertically for closing and opening the bottom compartment 16, and is guided in its movements by suitable vertical guides 18 provided in the cabinet at the opposite sides of its front portion. The guides 18 shown consist of metal channel strips which

are suitably secured, as by welding, to the side walls or upright side members of the casing for the outer door 13 and the side edges of the inner door 17 project into and are slideable vertically in these guide channels. When the front door 13 is open, the inner door 17 can be left in its down or closed position, shown in Fig. 1, in which it covers or closes the bottom compartment 16 of the cabinet, or it can be raised or slid upwardly to give access to the bottom compartment, as indicated in Fig. 2, as desired. The inner door slides up and down in front of the partition 14, which thus does not interfere with its movements.

When the drawer 11 is in place in the cabinet, the inner door 17 can be raised high enough to give the necessary access to the bottom compartment 16, but the door guides 18 are of such length as to prevent displacement or disengagement of the door therefrom while the drawer 11 remains in place in the cabinet. However, said guides, as shown terminate at their upper ends a distance below the top of the cabinet chamber or of the head member casing of the outer door 13 or other overlying portion of the cabinet, a distance at least equal to the vertical height of the inner door 17, or of the guide portions thereof which engage the guides 18, so that by first removing the drawer 11 of the cabinet, the inner door 17 can be raised to a position above or out of the upper ends of its guides 18 so as thereby to permit the placing of the door 17 in or its removal from the cabinet, as illustrated in Fig. 4.

Thus, it is possible for the manufacturer to make the cabinet equipped with the side guides 18 for the inner door 17, and if the purchaser requires a cabinet furnished with the inner door, it is only necessary to put the inner door in place in the cabinet in sliding engagement with its guides, whereas if the purchaser does not want to incur the additional cost of the inner door, the latter can be left out. In this way, with a single cabinet, the manufacturer or dealer can meet the requirements of the purchaser, giving him a lower priced cabinet without the inner door, or if the purchaser is willing to pay the additional price

for the inner door, all that is necessary is to insert the inner door into the cabinet and slip it into guiding engagement with its guides 18. No attached part or mounting device or element has to be detached to remove the door and no part has to be attached or provided for putting the door in place in the cabinet. It is only necessary for the manufacturer or dealer to have on hand the cabinets without the inner doors, and a supply of the inner doors, in order to supply a customer either with cabinets with or without the inner doors, and practically no labor or expense is involved in applying the inner doors.

In this application the cabinet is illustrated as being of sheet metal construction, but manifestly the provision for the attachable and removable inner door, as disclosed, is adapted for use with cabinets of wooden as well as metallic constructions. If it is desired to ventilate the compartment 16 which the inner door 17 closes, this can be done, for instance, by the provision of ventilating louvres 19 in the rear wall of the cabinet, as illustrated in Fig. 2.

I claim as my invention:

In a cabinet having a chambered casing with a front opening, a drawer movable forwardly and rearwardly in the upper portion of said casing, a partition dividing the casing chamber below said drawer into upper and lower compartments, and an outer door arranged to close the front opening of the casing below said drawer, the improved construction comprising a vertical inner door located in the casing in front of said partition and in rear of said outer door when the latter is closed, and guides at the sides of the casing beneath said drawer by which said inner door is guided to slide vertically in front of said partition for covering and uncovering said lower compartment when said outer door is open, the upper ends of said guides being spaced downwardly from the bottom of said drawer, when in position, a distance less than the height of said inner door, whereby said inner door is disengagable from said guides by upward movement only when said drawer has been removed.

JAMES H. DYETT.
